UPPER HOUSING FOR A TEST SCORING MACHINE

Perry Hall Rosen and Roy E. Seymour, Beaverton, and
Walter James Sirois, Sherwood, Oreg., assignors to
Automata Corporation, Richland, Wash.

Filed June 4, 1971, Ser. No. 150,259

Term of patent 14 years

Int. Cl. D10—05

U.S. Cl. D25—1 R

FIG. 1

FIG. 2

FIG. 3

FIG. 4

FIG. 5

FIG. 6

FIG. 7

FIG. 1 is a top and front perspective view of an upper housing for a test scoring machine showing our new design;

FIG. 2 is a front and bottom perspective view thereof;

FIG. 3 is a left side elevational view thereof, the right side being substantially a mirror image thereof;

FIG. 4 is a front elevational view thereof;

FIG. 5 is a rear elevational view thereof;

FIG. 6 is a top plan view thereof, and

FIG. 7 is a bottom plan view thereof.

We claim:

The ornamental design for an upper housing for a test scoring machine, as shown and described.
